(57) **CLAIM**

The ornamental design for a servo throttle motor shield, as shown and described.

DESCRIPTION

FIG. 1 is a perspective view of a servo throttle motor shield showing our new design;

FIG. 2 is a first side view;

FIG. 3 is a second side view;

FIG. 4 is a first end view;

FIG. 5 is a second end view;

FIG. 6 is a top view;

FIG. 7 is a bottom view; and,

FIG. 8 is a second perspective view showing the servo throttle motor shield in environmental use.
